UNITED STATES PATENT OFFICE.

ALFRED M. DEMUTH, OF CHICAGO, ILLINOIS.

DESIGN FOR A STEAM-DISTRIBUTER AND BASTER FOR COOKING APPARATUS.

54,835.

Specification for Design.

Patented Apr. 13, 1920.

Application filed August 21, 1919. Serial No. 319,033. Term of patent 14 years.

To all whom it may concern:

Be it known that I, ALFRED M. DEMUTH, a citizen of the United States, residing at Chicago, in the county of Cook and State of Illinois, have invented a new, original, and ornamental Design for a Steam-Distributer and Baster for Cooking Apparatus, of which the following is a specification, reference being had to the accompanying drawing, forming a part thereof.

Figure 1 is an elevation of a steam distributer and baster for cooking apparatus, showing my new design.

Fig. 2 is a view in perspective from the bottom thereof.

I claim:

The ornamental design for a steam distributer and baster for cooking apparatus as shown.

ALFRED M. DEMUTH.
